ATTORNEY

UNITED STATES PATENT OFFICE.

ALEXANDER S. HULDEN, OF GREAT FALLS, MONTANA.

PERMUTATION-PADLOCK.

1,218,084.

Specification of Letters Patent. Patented Mar. 6, 1917.

Application filed August 23, 1915. Serial No. 46,903.

To all whom it may concern:

Be it known that I, ALEXANDER S. HULDEN, a citizen of the United States, residing at Great Falls, in the county of Cascade and 5 State of Montana, have invented certain new and useful Improvements in Permutation-Padlocks, of which the following is a specification.

My invention relates to a new and improved permutation lock, which, in the present embodiment is shown in the form of a pad lock; and the principal object of the invention is to provide an improved lock of this character wherein the retainment and 15 releasement of the shackle is attained through the instrumentality of a series of permutation disks, the operation of which is extremely confusing to anyone not thoroughly conversant with its operation, yet 20 easy and simple to anyone who is aware of the correct method of manipulation.

Another object of this invention is to provide an improved lock of this type that is practically unbreakable by reason of its stout 25 and compact structure, thus guarding against surreptitious tampering and eliminating the liability of breakage in the event of powerful stress being subjected to certain parts thereof.

30 A further object of the invention is to provide a keyless padlock of the above type that is extremely simple in construction and which, it is believed may be manufactured at a comparatively low cost.

35 Various other objects and advantages will become apparent during the continuance of the following description.

The above and other objects which will 40 become apparent, are accomplished by such means as are shown in their preferred form in the accompanying drawings, described in the following specification and then more specifically pointed out in the appended claim.

45 In the accompanying drawings wherein like characters designate like parts throughout the several views:

Figure 1 is a view in front elevation showing my improved lock in its preferred embodiment.

Fig. 2 is a view in side elevation showing my invention in a similar capacity.

Fig. 3 is a view in vertical section illustrating parts of the device in elevation.

50 Fig. 4 is a view in horizontal section taken on line 4-4 of Fig. 1.

In the drawings the numeral 10 designates the body or parent structure of the lock which, of course, may be manufactured from any desired material. The body is provided 60 with a cut-out 11 which is arranged adjacent one side thereof (see Fig. 3) and while communicating with the upper face thereof, the same terminates short of its under face. In the lower wall of the cut-out 11 a circular recess 12 is formed, the purpose of which 65 will subsequently appear.

The body 10 is further provided with a series of openings 13 which communicate with the adjacent vertical edge thereof and the cut-out 11. For the purpose of receiving certain portions of the permutation disks (presently described) the wall of the cut-out 11 opposite the openings 13 is cut-out 70 as at 14 so as to provide a plurality of slots. 75

The permutation disks 15 are arranged in the slots 14, a portion of each disk projecting exteriorly of the body 10 through the openings 13. Of course it is to be understood that the disks 15 may be provided 80 with suitable numerals or other symbols in order that the correct positioning thereof may be attained. In the drawings I have shown each disk provided with a series of 85 numerals.

Each of the disks 15 are provided with an opening 16 which accommodates a stud 17. A small slot 18 is also formed in each of the disks 15 which communicates with the opening 16 and capable of permitting 90 the passage of lugs 19 that are formed on the stud 17. It will be understood that the disks 15 have to be so arranged whereby the slots 18 are brought into correct vertical alignment with the lugs 19 so as to permit the 95 removal, or rather slight upward movement of the stud 17. When in its normal locked position the stud 17 rests in the recess 12, the latter serving as an efficient seat therefor.

The upper end of the stud 17 is cut-out 100 as at 20, the said cut-out being provided with screw threads for the reception of the correspondingly formed end 21 of the shackle 22. In order to prevent continued rotation and the consequent dislodgment 105 of the shackle 22, a block 23 is fixed in the upper end of the cut-out 11, in proximity to the upper end of the stud 17. As the block 23 is provided with a central opening 110 the end 21 of the shackle may be readily received therethrough so as to engage the cut-out portion of the stud. The block 23 is

further provided with a shallow recess 24 in which normally rests a lug 25 which is carried on the shackle. Therefore it will be understood that when the stud 17 is in its 5 lowermost position in the body 10 the lug 25 will enter the recess 24 while the free end of the shackle 22 is locked within an aperture 26. However when the disks 15 are properly manipulated to bring the slots 10 18 into vertical alignment slight upward movement is permitted of the stud 17 which will cause the lug 25 to be removed from the recess 24 and the free end of the shackle 15 disengaged from the aperture 26. When the parts are in this position, the shackle 22 may be swung in either direction until the lug 25 engages the headed member 27 which of course prevents further movement. 20 In order to return the stud 17 to its lowermost position with the body 10 a resilient element, preferably in the form of a coil spring 28 is arranged thereabout, having one end fixed thereto while its other end bears against the block 23. 25 From the foregoing it is believed that the advantages and novel features of my invention will be readily understood and therefore further detailed description has been deemed unnecessary. 30 In reducing my invention to practice I find that the form referred to herein as the most practical and preferred embodiment is the most efficient, but realizing that certain conditions will necessarily vary in con- 35 currence with the adoption of my device, I

desire to emphasize the fact that various minor changes in the details of construction and in the proportion of parts may be resorted to when required without sacrificing any of the advantages of my invention as defined in the appended claim. 40

Having thus fully described my invention, what I claim as new and desire to secure by Letters Patent is:

In a permutation lock, a body structure 45 having a cut-out, a plurality of permutation disks arranged in said cut-out, a portion of each of said disks projecting exteriorly of said body structure, said disks provided with vertically aligned openings, a stud arranged 50 in said openings, lugs on said stud normally preventing removal thereof, said disks provided with slots capable of permitting passage of said lugs, a block having a central opening arranged in said first mentioned 55 cut-out, a shackle, one end of said shackle being connected with said stud, the adjacent portion of said shackle projecting through said block, a lug on said shackle, said block provided with a recess for the 60 reception of said last mentioned lug, and said body structure provided with a recess for the reception of the free end of said shackle.

In testimony whereof I affix my signature 65 in presence of two witnesses.

ALEXANDER S. HULDEN.
